UNITED STATES PATENT OFFICE

FREDERIC BARNES WALDRON, OF PRESCOT, AND JAMES HARRIS GRIFFIN, OF ST. HELENS, ENGLAND, ASSIGNEES TO PILKINGTON BROTHERS LIMITED, OF LIVERPOOL, ENGLAND

APPARATUS FOR THE GRADING OF ABRASIVES FOR USE IN CONTINUOUS GLASS GRINDING MACHINES

Application filed June 19, 1930, Serial No. 462,174, and in Great Britain July 12, 1929.

This invention relates to the grading of abrasives for use in continuous glass grinding machines and has for its particular objects to provide an improved continuously functioning horizontal flow grading apparatus, whereby abrasive of appropriate grade may be continuously supplied at successive stages of the grading operation to the respective parts of the grinding apparatus requiring those particular grades of abrasives.

Grading apparatus according to the invention comprises a channel increasing in cross-sectional area from the inlet to the overflow and has submerged partitions forming tanks in which the different grades of abrasive settle and from which they are continuously discharged to respective parts of the grinding apparatus, those portions of the channel in which the velocity is high being formed in a tank of greater cross-sectional area.

The apparatus further comprises the provision of a plurality of hoppers in which each tank terminates, the hoppers leading to discharge orifices from all of which approximately the same grade of abrasive is discharged downwards, and the walls of the hoppers are inclined at an angle to the vertical which is less than the angle of repose of the abrasive in water so as to ensure the fall of the material to the discharge orifices at the bottom of the hoppers.

For convenience of description, the abrasive dealt with is hereinafter regarded as sand, but it will be obvious that any other abrasive in granular or powdered form may be treated by the invention.

The invention will now be described by reference to the accompanying drawings which diagrammatically represent one constructional arrangement of apparatus embodying the improvements. In these drawings:

Figure 1 is a side elevation of said constructional arrangement with the end portion broken away;

Figure 2 is a plan of said arrangement;

Figure 3 is a cross-section through A—A of Figure 2 on an enlarged scale, and

Figure 4 is a longitudinal section of a por-

tion of the apparatus, also on an enlarged scale.

Throughout the different figures like reference numerals and letters are used to indicate like or corresponding parts.

In the arrangement illustrated, which is to be regarded only as a convenient example, the channel has four sections, the first section being formed by walls 1, the second by walls 2, the third by walls 3 and the fourth by walls 4. In the first section the walls 1 diverge from the inlet 5 to the full width of the channel in the second section. In the second, third and fourth sections the walls are parallel, but the width of the channel between them is greater in each section than in the preceding.

In the second, third and fourth sections, submerged partitions 6 divide up the channel into tanks, in which the different grades of abrasive settle. In the second section, each tank terminates downwards in four hoppers 7, each having a discharge orifice 8. In the third and fourth sections, each tank terminates in six hoppers 9 and eight hoppers 10 respectively, each hopper having a discharge orifice 8.

In the first section the velocity of flow of the mixture of abrasive and water, which is fed into the inlet 5, is so high that the turbulence caused by the flow prevents due settling of the abrasive between the partitions. The channel, therefore, with its walls 1, is formed in a tank having walls 11, the width between them being the same as that between the walls 2 of the channel in the second section.

The channel is provided with submerged partitions 12, and between the walls 1 and the walls 11 are partitions 13 reaching above the water level 14 (Figure 3). By this means the flow of water and abrasive is confined to the area in the channel between the walls 1 and above the partitions 12, while there is a comparatively stationary body of water and abrasive in the spaces in the tanks between the walls 1 and 11 and between the partitions 13. This body of water and the water in the hopper below is protected from the turbulence of the water between the par-

titions 12 and the abrasive in it is able to settle more quickly.

Each of the tanks in the first section, formed by the walls 11 and the partitions 12 and 13, terminates in four hoppers 7 with discharge orifices 8 similar to those in the second section.

Between the first and second, the second and third and the third and fourth sections are partitions 15 forming weirs and the fourth section terminates in a weir 16 over which the water flows into the overflow 17.

Immediately before the weirs 15 are troughs 18 with discharge pipes 19. The upper edges of the troughs are at such levels above the weirs 15 (see particularly Figure 4) as to maintain the heads of water which give the desired flow over the weirs.

In the continuous discharge of abrasive from orifices, difficulties are found from the banking up of abrasive on the sides of the hoppers. A passage is then formed through which water flows directly to the discharge orifice and this is followed by the fall of a mass of abrasive which frequently blocks up the discharge orifice.

According to the invention, these difficulties are surmounted in two ways. First the walls of the hoppers are inclined at an angle 20 to the vertical which is less than the angle of repose of the abrasive in water. Secondly, each tank has at least four hoppers from the discharge orifices of which the same grade of abrasive is discharged, and all these orifices discharge into a common pipe leading to the grinding runner or runners using the grade of abrasive.

By reason of the inclination of the hopper walls, the discharge of abrasive is more regular and the danger of the discharge orifices becoming blocked is minimized. By reason of the plurality of hoppers from which the same grade of abrasive is discharged, the supply of abrasive is not interrupted in the event of one of the discharge orifices becoming blocked.

Having described our invention, we declare that what we claim and desire to secure by Letters Patent is:—

1. In apparatus for grading abrasive and supplying it continuously, the combination of a channel along which the mixture to be graded flows, said channel increasing in cross-sectional area from the inlet to the overflow, submerged partitions in the channel forming tanks in which the different grades of abrasive settle and from which said grades are continuously discharged, and tanks of greater cross-sectional area than the channel extending over a length thereof at the inlet end, in which tanks the channel is formed.

2. In apparatus for grading abrasive and supplying it continuously, the combination of a channel along which the mixture to be graded flows, said channel increasing in cross-

sectional area from the inlet to the overflow, submerged partitions in the channel forming tanks, a plurality of hoppers constituting the downward termination of each tank leading to discharge orifices from all of which the same grade of abrasive is discharged, and tanks of greater cross-sectional area than the channel extending over a length thereof at the inlet end, in which tanks the channel is formed.

3. In apparatus for grading abrasive and supplying it continuously, the combination of a channel along which the mixture to be graded flows, said channel increasing in cross-sectional area from the inlet to the overflow, submerged partitions in the channel forming tanks, a plurality of hoppers constituting the downward termination of each tank leading to discharge orifices from all of which the same grade of abrasive is discharged, the angle of slope to the vertical of the hopper walls being less than the angle of repose of the abrasive in water, and tanks of greater cross-sectional area than the channel extending over a length thereof at the inlet end, in which tanks the channel is formed.

4. In apparatus for grading abrasive and supplying it continuously, the combination of a channel along which the mixture to be graded flows, said channel increasing in cross-sectional area from the inlet to the overflow, diverging walls forming a portion of said channel at the inlet end, a container having parallel walls between which said diverging walls are located, submerged partitions within the channel and partitions between the diverging walls and parallel walls extending above the water level, said partitions forming tanks in which different grades of abrasive settle and from which said grades are continuously discharged.

5. In apparatus for grading abrasive and supplying it continuously, the combination of a channel along which the mixture to be graded flows, diverging walls forming the inlet section of said channel, parallel walls forming further sections of said channel the width of each parallel-walled section being greater than that of the preceding parallel-walled section, a container having parallel walls between which said diverging walls are located, submerged partitions within the channel and partitions between the diverging walls and the walls of said container extending above the water level, said partitions forming tanks in which different grades of abrasive settle and from which said grades are continuously discharged.

6. In apparatus for grading abrasive and supplying it continuously, the combination of a channel along which the mixture to be graded flows, diverging walls forming the inlet section of said channel, parallel walls forming further sections of said channel the

width of each parallel-walled section being greater than that of the preceding parallel-walled section, a container having parallel walls between which said diverging walls are located, submerged partitions within the channel, partitions between the diverging walls and the walls of said container extending above the water level, said partitions forming tanks, and a plurality of hoppers constituting the downward termination of each such tank leading to discharge orifices from all of which the same grade of abrasive is discharged, the angle of slope to the vertical of the hopper walls being less than the angle of repose of the abrasive in water.

In witness whereof we have affixed our signatures hereto.

FREDERIC BARNES WALDRON.
JAMES HARRIS GRIFFIN.
